VIBRATOR.

1,124,808.

Specification of Letters Patent.

Patented Jan. 12, 1915.

Application filed May 13, 1912. Serial No. 696,808.

To all whom it may concern:

Be it known that I, EVEN J. ROHNE, a citizen of the United States, residing at Minneapolis, in the county of Hennepin and State of Minnesota, have invented certain new and useful Improvements in Vibrators, of which the following is a specification.

My invention relates to improvements in vibrators used in giving vibratory treatments to the surface of the human body, and consists particularly of a simple form of hand device adapted to be actuated through the medium of an alternating current working through electromagnets and an associated vibratory plate.

To this end the invention consists in the features of construction, combination, and arrangement of parts hereinafter described and claimed.

20 In the accompanying drawings forming part of this specification, Figure 1 is a plan view of my improved invention; Fig. 2 is a section on line $x-x$ of Fig. 1; Fig. 3 is a detail view of a vibratory plate forming part of the invention; and Fig. 4 is a dia- 75 grammatic view illustrating the wiring.

Referring to the drawings A represents the casing supported at one end by a handle 2, which handle preferably stands at an 80 angle with the casing to allow more convenient handling of the device. The casing is provided with a removable cover 3 formed with a central opening. Supported within the casing, as upon a plate 4, is a plurality 85 of electromagnets, each electromagnet being made up of windings 5 and core 6. Supported upon the plate 4 through the medium of a post 7 is an upwardly extending bent spring arm 8. Said arm at its 90 upper inwardly bent end forms a support for the vibrator B. The vibrator B is preferably made up as best shown in Fig. 2, consisting of a bottom plate 9 large enough in diameter to extend under the cover 3,

45 and a superimposed sheet 10 clenched over the edge of the lower sheet and curved upwardly to extend through the opening in the cover 3 to form a surface to be pressed against the part to be treated. Arranged within the vibrator and upon the bottom plate thereof is a conducting plate 20 insulated from the bottom plate by insulation 21. Positioned within the vibrator are granules 22 as of carbon to form the electric connection between the plate 20 and the

outer wall of the vibrator. Centrally supported on the plate 4 through the medium of an insulated post 11 is a coil spring 12, the coil spring supporting at its upper end a conducting post 13, as of carbon. The 60 conducting post 13, as shown in Fig. 2, will stand directly under the center of the vibrator B, and in operation will make contact with the plate 20 through the openings 23 in the bottom plate 9 and insulation 21. The circuit wires 14 and 15 will extend through the central opening 16 of the handle, the circuit being completed through the device as shown in Fig. 4. As shown the circuit is completed from the pole 17 suc- 70 cessively through the windings of the three electromagnets shown, the wiring of the last electromagnet being connected at 18 with the coil 12. From the coil 12 the circuit is completed through the conducting point 13, the plate 20, granules 22 and outer wall of the vibrator B, and the spring support 8 to the pole 19. In operation, of course, the poles 17 and 19 will be alternately positive 75 and negative poles of the circuit. 80

In use, when the circuit is completed by the connecting of the device with the current supply and the pressing of the vibrator against a surface to force the vibrator into conductive relationship with the conducting 85 point 13, the magnet cores 6 will be intermittently electromagnetized to attract the vibrator and draw the vibrator toward the cores by reason of the vibrator having spring support 8. When the cores are de- 90 magnetized between the alternations of the current the spring 8 assisted by the coil spring 12 will carry the vibrator back to normal position. The conducting point 13 thus acts as a resilient electrical contact for 95 the vibrator, being yieldable through the medium of the supporting spring 12 to allow the vibrator to be drawn into contact with the cores.

While I have shown three electromagnets 100 it will be apparent that a lesser or greater number may be employed without departing from the principles of my invention.

By means of the features of construction and arrangement shown and described I secure an extremely cheap and simple construction adapted for use with an alternating current and without the use of motor for actuation of the vibrator.

Through the medium of the spring sup- 110

port of the conducting post 13 which is independent of the spring support of the vibrator, I secure a construction in which the vibrator will be pushed away from the electromagnets independent of its own supporting spring. It is desirable to free the vibrator quickly and completely from the electromagnets. This is not always easy on account of the residual magnetism left 12 in the cores between current alternations, but it is rendered easy by having the two co-operating springs, the one for the vibrator and the one for the conducting post, as embodied in my construction.

15 I claim as my invention:

1. A vibratory device of the class described comprising a plurality of electromagnets connected in series, a vibrator yieldably supported adjacent to corresponding ends of the cores of said electromagnets, a conducting post having independent yieldable support adjacent the inner side of said vibrator, and alongside said electromagnets, and means for completing the circuit 25 of an alternating current through the coils of said magnets to and through said yieldably supported conducting post and said vibrator for the purpose set forth.

2. A vibratory device of the class described comprising a casing and a supporting handle, a plurality of electromagnets supported within said casing, a vibrator having spring support in position to be attracted by the cores of said magnets, a con-

ducting post having independent spring support adjacent the inner face of said vibrator and alongside said electromagnets, and means for completing the circuit of an alternating current through the windings of said electromagnets and to and through said 40 conducting post and said vibrator and its spring support for the purpose set forth.

3. A vibratory device of the class described comprising a plurality of electromagnets connected in series, a vibrator consisting of a bottom plate and spaced top yieldably supported adjacent to the corresponding ends of the cores of said electromagnets, a conducting plate supported upon said bottom plate and insulated therefrom, 50 said bottom plate being formed with an opening under said conducting plate, conducting granules loosely arranged in said vibrator, a conducting post having independent support adjacent the inner side of 55 said vibrator in alignment with the opening in the bottom plate thereof, and means for completing the circuit of an alternating current through the windings of said magnets to and through said conducting post and 60 said vibrator and contained granules for the purpose set forth.

In testimony whereof I affix my signature in presence of two witnesses.

EVEN J. ROHNE.
